BRINE TANK FOR ICE PLANTS

Filed Sept. 13, 1926

By *Norman H. Gay,*
Anton & Mason, Attorneys.

UNITED STATES PATENT OFFICE

NORMAN H. GAY, OF LOS ANGELES, CALIFORNIA

BRINE TANK FOR ICE PLANTS

Application filed September 13, 1926. Serial No. 135,134.

This invention relates to improvements in brine tanks for the manufacture of artificial ice, and particularly concerns elements for controlling the flow of brine through such tanks.

According to the present invention, a brine tank is provided for the reception of a number of individual ice cans, which are to be filled with water and immersed in the body of the brine, so that they are chilled sufficiently to convert the water to ice. These cans are held in position by certain walls within the ice tank, and it is customary to provide cooling pipes within the brine tank to maintain its temperature, and a circulation of the brine through the tank is effected to attain a uniform distribution of temperature at all parts of the tank.

According to the present invention, baffle plates are provided to prevent direct passage of the circulating brine from the inlet to the outlet of the tank along its bottom.

The drawing represents a longitudinal section through a brine tank of this type with a number of ice cans in position.

In this drawing, the brine tank is illustrated as having a bottom 10 with a number of upstanding U-straps 11 therein through which the brine may flow in its passage through the tank, which in the particular illustration is from the left toward the right. At the upper ends, these straps 11 are connected with the joists 12 having the cross joists 13 which maintain the covers 14 to protect the ice cans 15 against the entry of dirt. The ice cans 15 are supported within the compartments outlined by the joists 12 and 13 so that they are not swept away by the flow of brine through the tank.

The cooling pipes 16 are passed through the tank, usually at a height above the wall, since the brine in the tank is warmest near its top.

It will be noted that a space 18 is left between the bottom of each of the ice cans and the bottom 10 of the tank, through which the cold brine may pass directly from the inlet to the outlet of the tank without absorbing the calculated number of calories from the water contained within the ice

cans. In order to prevent this direct flow, a number of baffle plates 19 are secured to certain of the straps 11 to entirely block the direct flow of brine through the tank along its bottom, and to cause this brine to pass through the course illustrated by the arrows. In the particular illustration, these baffles have been illustrated as located at every alternate partition; but it will be understood that they may be located at other intervals, without departing from the intent of the present invention, which is that the direct flow of the brine should be impeded by forcing it to pass in a tortuous passage.

In the particular illustration, the baffles are brought upward to the level of the bottom row of cooling pipes 16. It is usually preferred to form the straps 11 of iron bars which are re-bent at the upper ends 11^a and secured to the joist 12. These straps have their sides at a sufficient distance to closely inclose the cooling pipes 16 and to hold them in position.

It is apparent that the invention is not restricted to the particular form of execution shown, but may be varied within the scope of the appended claims.

Having thus described the invention, what I claim as new and desire to secure by Letters-Patent, is:—

In a brine tank for ice making plants having an inlet and an outlet for brine at opposite ends thereof, cooling pipes extending through the tank and spaced from the bottom thereof whereby to cool the cold brine at the upper portions thereof, means to maintain the ice cans in position in the brine flow from said inlet to said outlet, said cans being located above the bottom of the tank and extending below said coils, and baffles arranged at the bottom of the tank across the line of flow of the brine and extending upwardly to said cooling pipes to prevent a direct flow of brine along the bottom of the tank beneath the ice cans while permitting a direct flow over the upper parts of the cans and over said cooling pipes.

In testimony whereof, I affix my signature.

NORMAN H. GAY. 100
